Primary Examiner — Selina Sikder*(74) Attorney, Agent, or Firm* — Knobbe Martens Olson & Bear LLP(57) **CLAIM**

The ornamental design for a component for electrical installations, as shown and described.

DESCRIPTION

FIG. 1 is a front right perspective view of a first embodiment of a component for electrical installations showing our new design.

FIG. 2 is a front elevational view thereof.

FIG. 3 is a bottom plan view thereof.

FIG. 4 is a top plan view thereof.

FIG. 5 is a right side elevational view thereof.

FIG. 6 is a left side elevational view thereof.

FIG. 7 is a rear elevational view thereof.

FIG. 8 is a front right perspective view of a second embodiment of the component for electrical installations showing our new design.

FIG. 9 is a front elevational view thereof.

FIG. 10 is a bottom plan view thereof.

FIG. 11 is a top plan view thereof.

FIG. 12 is a right side elevational view thereof.

FIG. 13 is a left side elevational view thereof; and,

FIG. 14 is a rear elevational view thereof.

The broken lines in the figures depict environmental features which form no part of the claimed design.
